[57] CLAIM

The ornamental design for a telephone set, substantially as shown and described.

DESCRIPTION

FIG. 1 is a front elevational view of a telephone set showing my new design, with the handset cradled in the stand, and with the pliable, convolutional cord normally connecting the end of the handset to the stand being shown in FIG. 7, but omitted in FIGS. 1-6 for convenience of illustration;

FIG. 2 is a rear elevational view thereof;

FIG. 3 is a left side elevational view thereof;

FIG. 4 is a right side elevational view thereof;

FIG. 5 is a top plan view thereof;

FIG. 6 is a bottom plan view thereof; and

FIG. 7 is a front perspective view from above with the handset removed from the stand and shown with the transceiver surface up, and the cradle of the stand exposed.
